[57] **CLAIM**

The ornamental design for a set of shelves with sliding track for hanging ornaments, as shown and described.

DESCRIPTION

FIG. 1 is a front elevation view of the set of shelves with sliding tract for hanging ornaments, with a cabinet shown in broken lines for purposes of illustration only and forming no part of the claimed design;

FIG. 2 is a top plan view thereof, it being understood that the top surfaces of all the shelves are identical;

FIG. 3 is a rear elevation view thereof;

FIG. 4 is a bottom plan view thereof, it being understood that the bottom surfaces of all the shelves are substantially the same, the only difference being the position of the hooks;

FIG. 5 is a left side elevation view thereof; and, FIG. 6 is a right side elevation view thereof.
